UNITED STATES PATENT OFFICE

CHARLES E. TIMSON, OF CHICAGO, ILLINOIS, ASSIGNOR TO WILLIAM COOPER & NEPHEWS INCORPORATED, OF CHICAGO, ILLINOIS, A CORPORATION OF ILLINOIS

MARKER OR TAG

Application filed September 19, 1932. Serial No. 633,803.

The present invention relates to markers or tags which are permanently sealed and applied to articles and things, and which, when applied, offer no uneven or projecting portions to catch some objects thus making the same subject to accidental removal. The invention further contemplates the provision of a marker or tag so constructed that when once applied, it cannot be removed 10 without breaking some part of the tag.

The invention has been herein illustrated and described in connection with markers or tags for attachment to animals, but it is susceptible for attachment to articles or things 15 of inanimate as well as animate nature.

The present invention relates to a marker or tag which may be rapidly and easily attached by anyone, and so constructed that it cannot be removed without being broken.

20 The invention is of the type comprising a strip of metal to form two arms, the end of one of which is fashioned to provide a pointed part and the other end of which is provided with an aperture or recess through 25 which the pointed part is passed and then clinched for permanently connecting together the ends of the strip in a manner to prevent removal without breakage.

An object of the present invention is to 30 provide a marker or tag which will cut its own hole so that it may be applied and fastened permanently in position by a single operation and so interlocked that it cannot be removed without breaking some part of the 35 tag.

Another object of the invention is to provide a self-cutting marker or tag which is permanently sealed against fraudulent or accidental removal.

40 A yet further object of the invention is to provide a marker or tag of simple construction which can be economically manufactured in quantity lots and readily applied in permanent position with minimum effort.

45 A still further object of the invention is to provide a marker or tag which may be easily applied to an article to be marked and when so applied cannot be removed without breaking some part of the tag.

50 The above, other and further objects of

the invention will be apparent from the following description, accompanying drawing and appended claims.

Tags of the present invention may be used for ear markers for cattle, for marking cattle or hides, or other articles or things, and as well may be used for permanent markers in connection with inanimate things where it is desired to have such things identified and marked.

Generally speaking, the invention contemplates a marker or tag formed of a strip of metal having a pointed part at one end and adjacent the other end a covered aperture through which the pointed part is forced and therein clinched and formed to permanently lock together the ends of the strip in a manner to prevent unlocking or removal of the tag without breaking some part of it.

An exemplification of the present invention is illustrated in the accompanying drawing and the views thereof are as follows:

Figure 1 illustrates an ear of an animal with a marker embodying principles of the present invention applied to the same.

Figure 2 is a plan view of the finished marker prior to bending into substantially U-shape for application to an article to be marked.

Figure 3 is an enlarged longitudinal vertical sectional view through a marker of the present invention, showing the relation of the parts with the pointed part disposed adjacent the aperture, and in dotted lines, appearance of the parts after the pointed part has been introduced into the cap immediately prior to deformation thereof by the squeezing of the parts together to provide interlock.

Figure 4 is an enlarged sectional view through a marker of the present invention showing the parts permanently fastened together after the pointed part has been forced home within the cap.

Figure 5 is an end view of Figure 3 partially in section.

Figure 6 is a sectional view taken substantially in the plane of line VI—VI of

Figure 4 and showing the mashed or deformed condition of the pointed part after it has been forced home within the cap and providing the enlargement preventing separation of the interlock and of the tag without breaking.

The drawing will now be explained.

The form of clip chosen to exemplify the present invention consists of a metal strip A having formed at one end a narrowed portion 1 terminating in a pointed part 2 and, near the other end, an aperture 3. On each side of the aperture 3 are slots 4 and 5 arranged one on each side of the aperture. The pointed part 2 is, in the manufacture of the illustrated embodiments of the tag, subjected to such action as to provide an enlargement which is pointed and sharpened thus providing a piercing extremity or tip wider than the portion 1. The pointed part 2 is weakened as by a perforation or hole 6. The lines defining the merger of the pointed part 2 with the portion or part 1 are curved, as are the lines forming the merger between the point 1 and the body of the strip A to prevent the formation of sharp shoulders or points or existing obstructions when the marker is secured in position.

The cap 7 of generally semi-circular form is provided with two lugs 8 and 9 and is applied to a strip A by passing the lugs 8 and 9 through the slots 4 and 5, respectively, with the ends of the lugs then turned up so that the free ends thereof enter the aperture 3 and form guideways for the pointed part or piercing tip of the marker as the piercing tip is forced into the cap.

The cap 7 has two indentations 10 and 11 formed in any suitable manner, which indentations extend inwardly of the general contour of the cap and between them define what is herein termed as a pocket 12. The pocket 12 is disposed above the slot or aperture 3.

The aperture or slot 3 is narrow and elongated and, preferably, extends transversely of the body of the tag.

The tag is formed from the strip A by bending into substantially U-shape and further bending the portion 1 so that the pointed part 2 is directed generally towards the aperture 3 ready for entry through said aperture and into the cap 7, when the tag is applied to an article, such as an animal's ear, a hide, or any other article to be marked.

The pointed part 2 is reduced in thickness, as may be readily observed from Fig. 3 and 5, which reduction in thickness provides a shoulder 13 to limit the approach of the arms of the tag when applied, to prevent squeezing of such arms.

The marker or tag of the present invention is permanently secured to a thing to be marked and cannot be removed unless some

part of the tag is broken, thereby permanently destroying the tag and preventing its re-use.

There have been placed on the market tags, of the general character of that herein illustrated, wherein the pointed parts have been curled when the arms were forced together. However, it has been found that unscrupulous persons may fraudulently remove such tags by prying apart the arms which causes an uncurling of the curled pointed part, thereby enabling unauthorized re-use of the marker.

The present invention provides an interlocking of the arms of the marker in such manner that some part of the marker or tag must be broken to remove it after having once been applied to an article.

The weakening of the pointed part 2 as, for example, by the provision of the perforation 6, is one way of making possible a tag wherein the pointed part may be mashed or deformed in such manner as to provide an enlargement preventing withdrawal of the pointed end from within the cap and thus preventing separation without breaking of some part of the tag.

The pointed portion 2 is reduced in thickness so that it may readily cut through an article with minimum damage and more easily be deformed or mashed within the cap. All the cutting is done by the pointed part 2 and none by the part below it, that is, the part indicated at 1 in the drawing.

The tag of the present invention is applied to an article by bringing the tag over the article and then forcing the pointed part 2 through the aperture 3, and against the underside of the cap 7 whereupon continuous pressure is applied to result in a mashing or deformation of the pointed part providing an enlargement preventing withdrawal of the pointed part from within the cap, and thus effectively locking together the ends of the tag.

This is accomplished by weakening the pointed part 2 as, for example, by provision of the perforation 6, and providing the pocket 12 in the cap 7 so that as the ends of the tag are brought together the pointed part will be prevented from curling along the underside of the cap because of the presence of such pocket 12 and thus be restrained against movement in any direction except widthwise of the pointed part, that is, in a direction of the length of the slot 3. The pointed portion 2 is, by this application of the tag, compressed so that the pointed part becomes elongated, as may be observed in Fig. 6. This elongation or deformation of the pointed part produces an enlargement or head which is greater in size in one direction than the slot 3 to thus prevent disengagement of the ends of the tag unless a portion of the tag be broken. Any attempt to pry apart the ends of the

tag will result in breakage of some part of the tag. The head or enlargement formed in the manner described might be broken or else the tag might be broken at the bend, 5 in any event the tag is so distorted in any attempt to remove it from the article to which it is fastened as to prevent its re-use and thus obviating dishonest use of tags of this character on articles other than the 10 one which should properly be marked by such tag.

The provision of the pocket 12 and the weakening of the pointed part 2 on the piercing tip, as before stated, results in a fore- 15 shortening of the pointed part 2 as it is forced home followed by a consequent elongation thereof widthwise, so that there is thus formed, during the squeezing together 20 of the arms of the tag to the point controlled by the provision of the shoulder 13, an enlargement or head within the cap which positively prevents fraudulent removal of the tag without destruction of some part of the same. Fig. 6 illustrates the elongation 25 of the pointed part 2 after it has been deformed and mashed in the manner described and shows how this mashed end is greater in length than the length of the slot 3 in the tag.

30 The end portion 1 preferably is reinforced by a rib 14 formed in it in any suitable manner.

The invention is claimed as follows:

1. A marking and sealing tag comprising 35 a bent metal strip having a pointed portion at one end and a cap covered aperture near the other end for receiving the pointed portion, said cap being provided with means to prevent the curling of the pointed portion when the same is inserted in the cap, the pointed portion being bent within said cap when said tag is applied in marking or sealing position, said pointed portion having a hole in it to weaken it so that when 40 the weakened portion is bent within the cap an enlarged end is produced to prevent withdrawal of the point from within the cap without breaking the tag and thus preventing re-use of the tag.

45 2. A marking and sealing tag comprising a bent metal strip having a point at one end and a narrow elongated aperture near the other end, a cap covering said aperture, the point being reduced in thickness and having a width substantially that of the length of the aperture, the cap having a pocket overlying the aperture for receiving the extremity of the point when the point is passed through the aperture and for 55 preventing curling of the point within the cap as the point is forced into the cap, the point being weakened so as to be mashed against the cap as the point is forced into the cap and prevented from curling by said pocket, the mashing of the point in the man-

ner stated providing an enlargement preventing removal of the point from within the cap without breaking the tag.

3. A marking and sealing tag comprising 70 a bent metal strip having a cap covered aperture adjacent one end and a pointed part at the other end, the pointed part being reduced in thickness and perforated so as to be readily deformed when forced into the cap, the cap being provided with a pocket to receive the pointed part and prevent curling thereof along the cap as said pointed part is forced home, the forcing home of 75 said pointed part in the pocket deforming it and providing an enlargement of the pointed part within the cap to prevent removal thereof from within the cap without breaking the tag.

4. A marking and sealing tag comprising 80 a bent metal strip having one end sharpened and perforated to provide a piercing tip and having near its other end a cap covered opening for receiving the sharpened end, said cap having a pocket for receiving said sharpened end for preventing the curling of said end along said cap as it is forced into the cap, the perforation in the sharpened end enabling a mashing and deformation of said end as it is forced home, the deformed end preventing removal 85 thereof from locking engagement within the cap without breaking some part of the tag.

5. A marking and sealing tag comprising 90 a bent metal strip having near one end a narrow elongated slot, a cap overlying said slot, said cap having a pocket formed in it, said strip having at the other end a pointed part sharpened and perforated to provide a 95 piercing tip, said pointed part having a width substantially that of the length of the slot and a thickness slightly less than the width of the slot, the tag being applied by forcing the piercing tip through an article and into the cap through said aperture, the cap pocket receiving the piercing tip and preventing curling thereof along the cap, the perforation weakening said tip so that application of force to introduce the tip 100 within the cap causes deformation of the tip widthwise thereof thus providing a resulting enlargement greater than the length of the slot to prevent removal of the tip from within the cap without breaking some 105 part of the tag.

6. A metal marker or tag adapted to have one end thrust through an article to be tagged and then interlocked with the other end of the tag, said one end having a weakened piercing tip which is deformable after 110 engagement with the other end of the tag, said other end being provided with means engageable by the piercing tip as the same is forced into engagement with said other end for preventing curling of the tip with- 115

120

125

130

in the tip-engaging means and for shortening and transversely enlarging said tip to provide an interlocking enlargement thereof precluding separation of the tag ends without breaking the tag.

- 5 7. A marking and sealing tag comprising a bent metal strip having one end sharpened and weakened to provide a piercing tip and having near its other end a cap covered 10 opening for receiving the sharpened end, said cap having means for preventing the curling of said sharpened end along said cap as it is forced into said cap, the weakening of the sharpened end enabling a mashing and deformation of said end as it is forced home, the deformed end preventing removal thereof from locking engagement within the cap without breaking some part of the tag.
- 15 20 8. A marking and sealing tag comprising a bent metal strip having a cap covered aperture adjacent one end and a pointed part at the other end, the pointed part being reduced in thickness and being weakened so as to be readily deformed when 25 forced into the cap, said cap being provided with a pocket to receive the pointed part and prevent curling thereof along the cap as said pointed part is forced home, the 30 forcing home of said pointed part in the pocket deforming it and providing an enlargement of the pointed part within the cap to prevent removal thereof from within the cap without breaking the tag.
- 35 35 In testimony whereof I have hereunto subscribed my name at Chicago, Cook County, Illinois.

CHARLES E. TIMSON.
